DESIGN FOR A SALT SHAKER OR THE LIKE

Marion Weeber, New York, N. Y., assignor to National Silver Company, New York, N. Y., a corporation of New York

Application February 25, 1948, Serial No. 144,714

Term of patent 14 years

(CL. D44—22)

To all whom it may concern:

Be it known that I, Marion Weeber, a citizen of the United States, residing in the city, county, and State of New York, have invented a new, original, and ornamental Design for a Salt Shaker or the like, of which the following is a specification, reference being had to the accompanying drawing, forming a part thereof, in which:

Fig. 1 is a side elevation of a salt shaker or the like, embodying my new design; and

Fig. 2 is a top plan view thereof.

The side opposite from that shown in Fig. 1 is similar to Fig. 1.

I claim:

The ornamental design for a salt shaker or the like, as shown and described.

MARION WEEBER.
